UNITED STATES PATENT OFFICE.

CLARENCE W. CARTER, OF MINNEAPOLIS, MINNESOTA, ASSIGNEE OF TWO-
THIRDS TO CHARLES S. TALBERT AND EMIL ZIMMERMANN, OF MINNE-
APOLIS, MINNESOTA.

CONCRETE BUILDING-BLOCK.

No. 800,719.

Specification of Letters Patent.

Patented Oct. 3, 1905.

Application filed July 14, 1904. Serial No. 216,482.

To all whom it may concern:

Be it known that I, CLARENCE W. CARTER, a citizen of the United States, residing at Minneapolis, in the county of Hennepin and State of Minnesota, have invented certain new and useful Improvements in Concrete Building-Blocks; and I do hereby declare the following to be a full, clear, and exact description of the invention, such as will enable others skilled in the art to which it app pertains to make and use the same.

My invention relates to the construction of artificial building-blocks from concrete and similar material, and has for its object to improve the same in the several particulars hereinafter noted.

It is a well-known fact that frost will readily pass through bodies of concrete and generally through stone, whether artificial or natural. Hence it has in practice, and especially in colder northern climates, been found necessary to "furnish out" the plaster applied to the interior of the walls of a building, whereas except for the passage of frost and moisture through the walls the plaster could be applied at much less expense and in a more satisfactory manner directly to the inner surfaces of the walls formed by the concrete blocks.

In accordance with my invention I construct the concrete body of the block with inner and outer sections and space these sections apart, but rigidly tie the same together by means of bridges or tie-plates, the ends of which are embedded and anchored in the said concrete sections and which bridges or tie-plates are constructed of wood or other rigid fibrous material, which is a poor or slow conductor of frost. In virtue of this construction the frost will not pass to any perceptible extent from the outer surface to the inner surface of a wall constructed of these improved building-blocks, and hence the plaster may without objection be applied directly to the inner surface of the said wall.

Several forms of the improved building-block are illustrated in the accompanying drawings, wherein like characters indicate like parts throughout the several views.

Figure 1 is a perspective view showing a building-block constructed in accordance with my invention; and Figs. 2 and 3 are

views corresponding to Fig. 1, but with parts broken away and illustrating slightly modified constructions.

The numeral 1 indicates the sections of the concrete body of block, which sections, as shown, are formed on their opposing faces with depressions or corrugations 2, leaving between them opposing projections 3, into which, as shown, are embedded the ends of wooden bridge-plates 4. These bridge-plates 4 preferably extend from the bottoms to the tops of the sections 1, and they serve to space apart, but rigidly unite, the said sections. With the bridge-plates 4 formed imperforate at their exposed portions and extended from top to bottom of the block the cavity between the concrete sections of the block is divided into a plurality of independent air-spaces.

In Fig. 1 the ends of the bridge-plates 4 are shown as formed with vertical grooves 5, which cause them to interlock with the said block-sections 1. In the construction illustrated in Fig. 2 nails 6, driven through the ends of the bridge-plates 4, interlock said plates to the block-sections 1. In the construction illustrated in Fig. 3 the ends of the bridge-plates 4 are shown as provided with perforations 7, into which the concrete when in plastic condition will run to interlock the said blocks and bridge-plates.

In the process of manufacture of said blocks a core or cores will be used to form the irregular or corrugated opposing surfaces of the concrete block-sections, and the bridge-plates will be suitably supported within the mold while the plastic concrete is forced around the ends of the same in the act of giving form to the said sections. When the concrete cement sets, the ends of the bridge-plates will be securely anchored in the concrete block-sections. Even when the ends of the bridge-plates are left smooth the concrete will firmly set around the same and adhere thereto. The so-called "bridges" or "bridge-plates," it will of course be understood, may take a great many different forms, and it will also be understood that the concrete sections of the block may be given any desired or suitable form.

What I claim, and desire to secure by Letters Patent of the United States, is as follows:

A building-block having its body constructed in sections formed of concrete, and bridge-plates constructed of fibrous material which is a poor conductor of heat and moisture, said bridge-plates having their ends embedded in said concrete sections, to rigidly unite, but space apart, the same, the said bridge-plates extending from bottom to top of said concrete block-sections, and di-

viding the space between the same into compartments, substantially as described.

In testimony whereof I affix my signature in presence of two witnesses.

CLARENCE W. CARTER.
